United States Patent Office

Des. 180,496
Patented June 18, 1957

180,496

COMBINED DESK SET AND NAME PLATE

John W. Sorenson, East Grand Rapids, Mich.

Application July 25, 1956, Serial No. 42,388

Term of patent 14 years

(Cl. D74—1)

Fig. 4.

Fig. 1 is a side perspective view of a combined desk set and name plate showing my new design;

Fig. 2 is a side elevational view thereof;

Fig. 3 is a top plan view;

Fig. 4 is a rear elevational view thereof.

The essential features of my design reside in the portion shown in solid lines on the drawing.

I claim:

The ornamental design for a combined desk set and name plate, as shown and described.
